Assistant Examiner — Marissa J Cash

(74) Attorney, Agent, or Firm — Avyno Law P.C.

(57) **CLAIM**

I claim the ornamental design for drone for kids, as shown and described.

DESCRIPTION

FIG. 1 is a front perspective view of a drone for kids. FIG. 2 is a front view of the drone for kids of FIG. 1. FIG. 3 is a rear view of the drone for kids of FIG. 1. FIG. 4 is a top view of the drone for kids of FIG. 1. FIG. 5 is a bottom view of the drone for kids of FIG. 1. FIG. 6 is a side view of the right side of the of the drone for kids of FIG. 1; and, FIG. 7 is a side view of the left side of the drone for kids of FIG. 1. In the drawings, the broken lines depict environmental subject matter only and form no part of the claimed design.

1 Claim, 5 Drawing Sheets
